UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,109,697.

Specification of Letters Patent.

Patented Sept. 8, 1914.

Application filed June 29, 1907. Serial No. 381,411.

To all whom it may concern:

Be it known that I, WILLIAM H. MUZZY, a citizen of the United States, residing at Dayton, in the county of Montgomery and 5 State of Ohio, have invented certain new and useful Improvements in Cash-Registers, of which I declare the following to be a full, clear, and exact description.

This invention relates to improvements in 10 cash registers, and has more particular relation to improvements in registers of the multiple department or multiple totalizer.

The object of the invention is to provide 15 mechanism whereby a number of articles may be registered on the machine and only the total amount of these articles disclosed to the customer, while the details and total are printed upon the record strip and only the total on the check.

20 Another object of the invention is to provide a plurality of independent accounting mechanisms for different classes of goods, and a further mechanism for accounting to the customer for the sum total of all of the 25 goods which may have been entered on the different individual accounting devices.

With these and incidental objects in view, the invention consists in certain novel features of construction and combinations of 30 parts, the essential elements of which are set forth in appended claims and a preferred form of embodiment of which is hereinafter specifically described with reference to the drawings which accompany and form part 35 of this specification.

Of said drawings: Figure 1 is a transverse sectional view of a type of machine well known in the art, with my improvements applied thereto. Fig. 2 is a detail elevation, partly in section, of the turn-to-zero mechanism for the indicators. Fig. 3 is a 40 partial rear elevation of the type of machine shown in Fig. 1. Fig. 4 is a detail transverse sectional view of the type carriers and their operating pinions. Fig. 5 is a transverse sectional view taken on the line 5-5, looking in the direction of the arrow shown in Fig. 3. Fig. 6 is a detail top plan view, 45 partly in section, of the platens for the detail strip and their co-operating parts. Fig. 7 is a transverse sectional view taken on the line 7-7, looking in the direction of the arrow shown in Fig. 3. Fig. 8 is a detail elevation, partly in section, of the type carrier setting mechanism. Fig. 9 is a partial front 50

5 elevation of the indicators and the connecting gearing for the total type carriers. Fig. 10 is a side elevation of the multiple counter mechanism. Fig. 11 is a side elevation, partly in section, of the setting lever for the 60 multiple counter mechanism. Fig. 12 is a transverse sectional view through the machine, showing the special key and some of the parts controlled thereby. Fig. 13 is a transverse sectional view, partly broken 65 away, through the machine, showing the check levers controlled by the special key. Fig. 14 is a detail side elevation of the intermediate gear and the cam disk connected thereto for operating the inking pads. Fig. 70 15 is a detail top plan view of the inking pads; and Fig. 16 is a detail side elevation of the cam disk for operating the indicator idle pinion mechanism.

In registers at present on the market, it 75 has been customary when it was desired to register or record different details of a transaction in different departments, to effect this result by successive operations of the machine, which registered or recorded the detail amount in a particular accounting device; but in such machines the sum total of all the articles of that particular sale was not indicated to the purchaser, nor was a check issued for such sum total, nor was the 80 sum total recorded on the detail strip. In the present invention, however, there is provided means whereby the sale of any different character of merchandise may be recorded on individual accounting devices; the 85 indicators of the accumulator or totalizer finally to show the sum total of all the different amounts entered in the different accounting devices, the record strip to show the details and sum total, and a check to issue 90 showing this sum total without such details of the transaction.

As an illustration of my invention the invention is shown as applied to a multiple totalizer machine of the type shown in the 95 patent to Thos. Carroll No. 754,049, issued March 8th, 1904, and which is at present well known upon the market. In this machine the different totalizers, which may be brought successively into operation, may be allotted to different characters of merchandise: such as cigars, wines, café or any other designation relating to the merchandise of a general store. Should a customer purchase 100 during one transaction a number of such ar- 110

ticles, they are registered successively upon their respective totalizers and the sum total finally disclosed to the purchaser through the indicators of the accumulator or totalizer 5 or by means of the printed check.

The present machine is shown as operating manually, but it will of course be understood that if speed is desired, any of the regular forms of electric motors may be applied to it substantially in the same manner 10 as the machines at present on the market.

The keys 1 control the variable movement of the segment 2, which is transmitted to the total registering mechanism 3 through 15 the intermediate gears 4, pinions 5 and 6, the double width clutch pinion 7, lever 8, link 9 and the cam disk 10. The gear 4 also meshes with a pinion 11 loosely mounted upon a shaft 12. Adjacent to this pinion is a similar pinion 13, see Fig. 9, which is attached to one end of a short sleeve 14, to the other end of which is secured an indicator 15. For 20 each bank of keys 1, of which they are three, there is an indicator 15, and in addition an extra one to which is transferred the number 25 of rotations of the third indicator. Pinions 16, which are the same width as the combined width of pinions 11 and 13, are mounted in the upper ends of rock levers 17 which are pivoted intermediate their ends upon sleeves 18 hereinafter referred to. The lower ends of the levers are united by a transverse rod 19 which extends through 30 semi-circular slots 20 formed in the gears 4, see Figs. 1 and 16. The left hand end lever 17 is further provided with a depending portion 21, which carries a roller 22 that plays in a cam groove 23 formed in the disk 24 which in turn is secured to a rotatable shaft 25, see Fig. 16.

The shape of the cam grooves in the disks 10 and 24, the former being also secured to the shaft 25, are such that the segments 2 and the gears 4 are returned to normal position before the pinions 7 and 16 are thrown into mesh with their respective pinions. Just as the segments 2 start to take up a new position, the pinions 7 and 16 will be rocked rearwardly into engagement with 50 their respective pinions so that the rearward movement of said segments will also be transmitted to the registering and indicating mechanisms. Each of the gears 4 carries a segmental plate 27 which is provided with 55 V-shaped notches 28 into which a pawl 29 secured to a rock shaft 30 is rocked, immediately after the segment 2 has taken up its new position, by a cam 31 secured to the shaft 25 engaging a roller 32 secured to the lower end of an arm 33, the upper end of which is fastened to the shaft 30.

Immediately after the pawls 29 are rocked into engagement with the plates 27, the pinions 7 and 16 are rocked out of mesh with 60 their respective pinions. The pawls 29 re-

main in engagement with the plates 27 until the beginning of the next operation of the machine, when they are rocked out of engagement by a coil spring 34 surrounding a pin 36 which has one end extending through 70 an ear 37 projecting laterally from the arm 33. The other end of said pin is enlarged and abuts against the back frame 38 of the machine. The ends of the coil spring 34 abut against the enlarged head of the pin 36 75 and the ear 37 of the arm 33, so that when the high portion of the cam 31 passes beyond the roller 32, the spring will expand and rock the arm and thereby the pawls 29 out of engagement with the plates 27. The purpose 80 of the arms 29 is to prevent accidental movement of the gears 4 and the segments 2 between operations of the machine.

It will be seen from the foregoing description that the registering and indicating mechanisms are left in the position to which they are moved, while the segments 2 and the gears 4, as described in said patent, are returned to normal position during each operation of the machine.

It is desirable in the present machine, to conceal the indicators of the accumulator or totalizer during the registration of different items and to expose them only after the total of all the items has been accumulated upon 95 said indicators. This is accomplished in the following manner: When the keys representing the amount of the last item to be registered are depressed, the "total" key 39, see Fig. 12, is also depressed. The actuation of this key will raise its detent 40, thereby allowing the retaining bar 41 to be drawn rearwardly by its spring 42 and consequently latch the key in its depressed position. One end of a link 43 is connected to the retaining 100 bar, while the other end is connected to an arm 44 secured to a shaft 45. The upper end of the arm 44 has ears 46 and 47 projecting laterally in opposite directions, see Fig. 9, and which in turn are provided with anti-friction rollers 48 and 49 respectively. A collar 50 is splined upon the shaft 25 by a key 51, so as to allow a lateral movement of the collar independent of the shaft 25 but to enforce a rotary movement of the collar with 110 the shaft. This collar is provided with notches 52 which are engaged by a spring pressed plunger 53 carried by the shaft 25, so as to hold the collar in either of the two positions to which it may be adjusted. This collar is also provided with camming projections 54, 55 and 56; the first two being adapted to engage with the rollers 48 and 49, and the last one with the rollers 57 and 58 secured to the flash operating arm 59 and the indicator turn-to-zero arm 60 respectively.

The arm 59, see Fig. 12, is pivoted at its upper end to another arm 61, which in turn is pivotally mounted at its inner end upon 120

the shaft 12. At its outer end the arm 61 has secured to it one end of a flash 62, the other end of which is fastened to a similar arm. The flash is drawn into position to conceal the indicators by a spring 63, which has one end fastened to the arm 61 and the other end to a pin 64 secured to the register frame. The flash is limited in its upward movement by the end of an elongated slot 65, cut in the lower end of the arm 59, coming in contact with the shaft 25.

When the "total" key is depressed the retaining bar 41 is drawn rearwardly by its spring 42 carrying with it the link 43 there-
15 by rocking the arm 44, so as to bring the roller 48 into the path of the camming pro-
jection 54 secured to said collar, with which the beveled portion 54^a engages after the
20 shaft has been given a little over a quarter turn and cams the collar into the position shown in Fig. 9. As the shaft completes its revolution, the projection 56 of said collar engages the roller 57 secured to the arm 59 and withdraws the flash 62 to expose the
25 amount indicators 15 of the accumulator or totalizer and a stationary indicator 66 which bears the inscription "Total" and which is mounted upon the shaft 12. The flash is held in its withdrawn position against the
30 tension of the spring 64 by the projection 56 remaining in contact with the roller 57 until the commencement of the next operation. It is to be understood that the "total" key and the amount keys are released near
35 the end of the operation of the machine by the shoulders 67, formed upon the cams 68 secured to the rock shaft 69, coming in contact with the rollers 70 projecting from the retaining bars 41 as is well understood in
40 this type of machine, see Fig. 12.

After the total has been displayed by the indicators of the accumulator or totalizer, the indicators must be returned to zero or cleared before starting to accumulate a new sum. This I have accomplished by the following means: Fastened to the amount indicators 15, see Figs. 2 and 9, are disks 71 of the same diameter as said indicators. These disks are equipped with heart shaped
45 cam grooves 72 and V shaped notches 73, the latter being engaged by pawls 74 loosely mounted upon the shaft 30 and forced into engagement with the notches by springs 75 which surround the shaft and have their
50 opposite ends supporting the pawls and attached to the back frame. Arms 76 carrying at their upward and forward ends rollers 77 which play in the heart shaped grooves 72 are also loosely mounted upon the shaft
55 30. Each arm 76 has a projection 78 which extends below the shaft 30 and is engaged by a transverse rod 79 secured at one end to the indicator turn-to-zero arm 60 and at its other end to an arm 79^a, see Fig. 3, piv-
60 eted upon the shaft 30. The pawls 74 are

for keeping the indicators in proper alignment, while the arms 76 are used to turn the indicators to zero. When each roller 77 occupies the position in the cam groove 72 as shown in Fig. 2, the indicators are at 70 zero. It will be seen by reference to said figure, that if the roller 77 should occupy any other position in the cam groove and be forced toward the axis of the indicator, the latter would be rotated by the said roller 75 passing along the cam groove toward the shaft 12 until the roller rests in the notch 12^a, at which time the indicator would be at zero. Each arm 76 is rocked to turn its indicator to zero by the rod 79 contacting 80 with the projection 78.

It will be seen from the above description that when the collar 50 is in its left hand position, the cam 56 is out of alignment with both the rollers 57 and 58, and the rotation of the sleeve with the shaft will have no effect upon either the flash or the turn-to-zero mechanism for the indicators. When the "total" key is depressed however, as before described, and the arm 44 rocked rearward, the projection 48 will be brought into the path of the incline block 54. As the shaft 25 now starts its rotation, the cam 56 is moved by the end of the roller 58, and slightly after this period the cam 95 block 54 contacts with the roller 48, which cams the sleeve 50 to the right thus bringing the cam 56 in alignment with the roller 57, so that the flash is thereafter drawn downward and held so, to expose the total 100 indication, as shown in Fig. 9. At the end of the operation the "total" key 39 is of course released and the different parts allowed to assume their normal positions, thus bringing the roller 49 into the path of the 105 incline projection 55. The location of the projection 55 is such, that during the first part of the succeeding operation of the machine the cam 56 will operate on the roller 58 and return the indicators to zero or clear 110 them. The sleeve 50 will then be shifted before the cam 56 reaches the roller 57, so that the flash will remain up, concealing the indicators.

The differentially movable segments 2, 115 see Fig. 1, carry anti-friction rollers 80, which play in elongated slots 81 formed in upright pivotal arms 82. These arms are secured to the inner ends of a series of nested sleeves 83, which extend out to one 120 side of the machine and have fastened at their other ends segmental racks 84, see Figs. 3, 4 and 8. These racks mesh with pinions 85 which are secured to one end of another series of nested sleeves 86, to the 125 other ends of which are fastened printing wheels 87, which will be known hereinafter as the detail printing wheels, so as to be more clearly distinguished from another set of printing wheels to be described later. 130

The indicators 15, see Figs. 1 and 3, have attached to their sides, opposite the disks 71, gear wheels 88, which mesh with pinions 89 secured to shafts 90, which extend through one side of the machine and have attached to their outer ends pinions 91, similar to the pinions 89. The pinions 91 mesh with gear wheels 92, which carry pinions 93 of the same pitch and diameter as the pinions 89 and 91. Mounted upon one of the side frames 94 of the machine are large gear wheels 95 which mesh with the pinions 93 located above and pinions 96 located below said wheels. The pinions 96 are secured to one end of nested sleeves 97 which carry at their other ends total printing wheels 98, see Fig. 4. The detail and total printing wheels, and their connected parts, are mounted upon a shaft 99 which is supported in two of the side frames 94.

It will be seen from the above description that the pinions 89 and 91 simply act as idlers to transmit the movements of the indicators to the gear wheels 92. The pinions 93, which are pinned to the sides of the wheels 92, receive the same degree of movement as the latter. This movement of the pinions 93 is transmitted to the pinions 96 by the intermediate gears 95. The pinions 96, as shown in Fig. 5, are twice the diameter of the pinions 93, so that a complete rotation of the latter will turn the former only a half rotation. This is to permit the printing from the type wheels 98, which are connected to the pinions 97, of a check and a detail strip as hereinafter described.

In order that the indicators and the total printing wheels may be brought to the proper position to indicate and record the accumulation of a plurality of items, it is necessary to provide a transfer mechanism, and as the indicators and total printing wheels are connected a single transfer mechanism will answer for this purpose. Referring to Figs. 3, 5, 7 and 9, the said transfer mechanism will now be described: The pinions 93 are secured to one end of a series of nested sleeves 100, which surround the indicator shaft 12, which is slightly reduced at this end, see Fig. 9. The sleeves carry at their opposite ends a disk 101 and three ratchet wheels 102, the disk and the first two ratchet wheels being provided with laterally projecting pins 103. It will be seen from the above description, that the disk 101 and the ratchet wheels 102 being connected with the pinions 93, will move in unison with the indicators 15; the disk 101 with the cents indicator, the ratchet adjacent to the disk 101 with the dimes indicator, the middle ratchet with the units of dollars indicator and the end ratchet with the tens of dollars indicator. Upon a transverse shaft 104 which nearly extends the entire width of the machine, is pivotally mounted a frame 105

carrying the transfer mechanism. This frame has a rearward projection 106, see Fig. 5, which is provided with an anti-friction roller 107, that plays in a cam groove 108 formed in a disk 109 fast to the rotary shaft 25. Just after the first quarter turn of the shaft 25, the frame 105 will be rocked slightly upward, carrying the trip pawls 110, mounted in the upper part of said frame, into the path of the pins 103. These pins are so located that when the indicators are passing from 9 to 0 the pins will rock the pawls 110, against the tension of their springs 111, out of engagement with the lateral projections 112, thereby allowing the transfer pawls 113 to drop into engagement with the ratchet wheels of the next higher denomination and advance same one step near the end of the rotation of the shaft 25, by cams 114 arranged successively upon the said shaft coming into contact with rollers 115, see Fig. 7, mounted upon the lower rear ends of the transfer pawl carriers 116. These pawl carriers are normally held in a retracted position by coil springs 117, the opposite ends of which are connected to the pawl carriers and the frame 105. This frame is cammed back to normal position by the cam disk 109 at the end of rotation of the shaft 25. This form of transfer is well known in the art and, it is thought, needs no further description. The form of the groove in the cam disk 109 is such that the frame 105, as above stated, returns to a retracted position at the end of the operation of the machine, so that the noses 110^a of the transfer trips are moved out of the paths of the pins 103. The object of this construction is to prevent the transfer pawls being tripped during the time that the indicators are being returned to zero by the heart shaped box cams. After the period of action of the heart shaped cams is past, the frame 105 is again moved forward to bring the noses 110^a into the paths of the pins 103.

Pivottally mounted upon the nested sleeves 86 and 97 are bell-cranks 118 and 119, see Figs. 7, 14 and 15, the outer ends of which are connected by short shafts 120 and 121. Upon the shaft 120 is mounted a support 122 for an ink pad 123, and supports 124 and 125 carrying ink pads 126 and 127 are similarly mounted upon the shaft 121. Blocks 128 secured to the sides of the bell-cranks 118 and 119, carry spring pressed plungers 129 which contact with flat portions 130 of the supports 122, 124 and 125 and thus hold the ink pads 123, 126 and 127 slightly away from the detail and total type carriers 87 and 98. The operating crank 131, which requires two rotations for a complete operation of the machine, carries a pinion 132 which meshes with a gear 133 four times its size, so that two rotations of the crank handle 131 turns the gear 133 a half revolu-

tion. A disk 134 is suitably secured to the gear 133 and is provided with a cam groove 135. A plate 136 is bifurcated at its upper and lower ends, the upper end of which 5 straddles and is arranged to be guided by the axis 137 of the gear 133, while one side of the lower bifurcated end of the plate 136 is provided with teeth 138, which mesh with a pinion 139 secured to the side of the bell 10 crank 119. The configuration of the cam groove 135 is such, that for each half turn of the gear 133 the plate 136 is first lowered, bringing the ink pads over the upper and lowermost types on the wheels 87 and 98, at 15 which point they are momentarily arrested and then returned to normal position. The gear 133 meshes with a gear 140 half its size and which therefore receives a complete rotation for each half turn of the gear 133, 20 see Fig. 7. This gear 140, which is secured to the shaft 104, meshes with a similar gear 141 fastened to the shaft 25. Pinned to the gear 141 is a smaller gear 142, which meshes with a similar gear 143 secured to the inner 25 end of a short transverse shaft 144, see Fig. 3, which is supported by the printer frame 145. To the outer end of the shaft 144 is attached a gear 146, which meshes with a gear 147 that in turn drives a gear 148, 30 which meshes with a similar gear 149. To the shaft 144 is pinned a disk 150 which is provided with a cam groove 151, in which plays a roller 152 secured to the upper and rearward end of a bell crank 153, see Fig. 5, 35 the forward end of which is provided with a platen lever 154 connected thereto by adjusting bolts 155, in substantially the same manner as shown and described in the aforementioned patent. The bell crank 153 is 40 pivotally mounted upon a stub shaft 156 secured to the printer frame. At the forward end of the lever 154 is mounted a platen roller 157 around which passes a record strip 158 led from a supply roll 159, mounted 45 upon the back frame 38 of the machine, see Fig. 7, over a guide pin 159^a to a storage roll 160 secured to a ratchet disk 161, mounted upon a stub shaft 162, of an upright arm 163 of the platen lever 154. Also mounted 50 upon the stub shaft 156 is another platen lever 164, see Fig. 6, which carries a roller 165, similar to the platen roller 157, and around which the record strip 158 also passes. A link 166, see Figs. 5 and 6, is 55 mounted upon the stub shaft 156 by means of an elongated slot 167 formed in its rearward end, and at its forward end it is bifurcated and straddles a pin 168 projecting laterally from the platen lever 164. The 60 link is prevented from lateral displacement by the enlarged head of the pin and a collar 169 surrounding the inner end of said pin.

A pin 170 projects from the platen lever 154 to a position normally in front of the 65 bifurcated portion of the link 166. The

extreme rear end of this link enters a recess 171 of a disk 172 secured to the right hand end of the shaft 45, which is controlled by the "total" key. The upper side of the slot 171 is cut at such an acute angle, that 70 if the machine be operated without depressing the "total" key the disk 172 will hold the link in normal position and consequently the lever 164 and the platen roller 165. The link 166 is normally forced rearwardly by 75 a light coil spring 173, which surrounds a collar placed upon the shaft between the link and the hub of the lever 164. The opposite ends of said spring are attached to the link 166 and the above mentioned hub. 80 If the "total" key is depressed the shaft 45 will be rocked in the direction of the arrow shown in Fig. 5, the disk 172 carried thereby camming the link 166 forward so that its bifurcated front end will straddle the pin 85 170 of the lever 154 as well as the pin 168 of the lever 164 and thereby couple the two levers. A pawl 174 carried by the link 166 will be forced downwardly by a leaf spring 175, so as to hook over a projection 176 90 mounted upon the platen lever 154 and thus hold said link in a forward position regardless of the disk 172.

Just after the impression has been made upon the record strip, a pin 176^a mounted 95 upon the cam disk 150 contacts with the rear upturned end of the pawl 174, and rocks the forward end out of engagement with the projection 176, permitting the spring 173 to withdraw the bifurcated end of the slide out 100 of engagement with the pin 170, and thereby uncouple the platen levers 154 and 164 which remain uncoupled until the "total" key is again depressed.

The configuration of the cam groove 151 105 formed in the disk 150, is such that upon each operation of the machine the platen lever 154 will be rocked twice and the lever 166 rocked a similar number of times if coupled to the lever 154. The throw of the 110 lever 154 the first time it is rocked is less than its second movement, the purpose of which will now be described: The shape of the cam grooves 135 and 151 is such, that when the ink pads are momentarily held over the upper and lowermost types by the cam groove 135, the lever 154 will be given its first rocking movement, which is sufficient to carry the ink pad 127 into contact with the detail type wheels 87, by striking the pad support 125. If the lever 164 is coupled to the lever 154 by an operation of the "total" key, as hereinbefore described, it will receive the same degree of movement and consequently ink the total printing 115 120 wheels 98 by the platen roller 165 coming in contact with the pad support 124, thereby carrying the ink pad 126 into contact with said wheels; the rollers 157 and 165 are then 125 returned to normal position, and also the ink- 130

ing pads, after which the rollers 157 and 163 are again depressed, this time carrying the record strip into contact with the inked type wheels 87 and 98 thereby taking an impression upon said strip. The downward movements of the lever 154 will also carry the ratchet disk 161, over which idly plays a spring pressed feed pawl 177 mounted upon the outer end of an arm 178, the other end of the latter being pivotally mounted upon the stub shaft 162. As the lever 154 returns to normal position, the pawl 177 will rotate the ratchet disk 161 thereby feeding the record strip as fully described in the aforementioned patent. It will be seen from the above description, that upon each operation of the machine the lever 154 will be rocked to ink the detail type wheels 87 and then to take an impression upon the record strip from said wheels; but the lever 164 will only be rocked to take an impression from the total printing wheels 98 upon the operation of the "total" key 39.

The check strip 179 passes under the total printing wheels 98 only and is fed forward only upon the operation of the "total" key 39. The lower wheel 149 of the chain of gearing previously described, is attached to the side of a feed roller 180, see Figs. 3 and 7, which is rotatably mounted upon a shaft 182 having eccentric bearings mounted in the printer frame. The gear wheel 148, which meshes with the wheel 149, is attached to the side of a printing cylinder 183 which carries numbering wheels and an electro, for printing upon the check strip 179 the consecutive number and any suitable advertisement. To the side of the feed roller 180 is secured a disk 184 equipped with a cam groove 185, similar in shape to the groove 151 for operating the platen lever 154, in which plays a pin 186 projecting laterally from a lever 187 pivotally mounted at its rear end to the printer frame 145. The forward end of the lever 187 is attached to a vertically movable slide 188, which is guided by suitable standards 189. The upper end of the slide is provided with a platen 190 for taking an impression upon the check strip 179 from the total printing wheels 98. When the machine is operated without depressing the "total" key the gear 149, roller 180 and the cam disk 184 will be rotated, reciprocating the platen twice but not giving it sufficient throw to ink the type or take an impression: neither will the check strip be fed forward on account of the printing cylinder 183 and the feed roller 180 being slightly separated.

Referring now to Fig. 13, it will be seen that upon an operation of the "total" key a pin 191 carried thereby will move a longitudinally sliding plate 192 rearwardly. This plate is provided with an elongated slot 193 and bifurcated ends 194 and 195.

The slot 193 and the end 194 straddle the rock shaft 69 and a pin 195 respectively, which act as guides for said plate. When the plate is moved rearwardly against the tension of its spring 197, a roller 198 carried by said plate will pass beneath, and in the path of a bevel face 199 formed upon an arm 200 secured to the rock shaft 69. This rearward movement given to the plate 192 by the operation of the key 39, will bring the end of the bifurcated portion 195 into contact with a pin 201 secured to a lever 202, which is provided with a bifurcated front end 203 that straddles the shaft 69 and at its rear end is attached to a short vertical arm 204 secured to a transverse shaft 205. The lever 202 is held in the position shown in said figure by a spring 206, which is connected at one end to one of the legs formed by the bifurcated portion 203 and at its other end to a pin 207 mounted upon the machine frame. Shafts 25 and 69 have projecting downwardly from them arms 208 and 209 respectively, which are connected by a link 210, so that by a complete rotation of the shaft 25, the shaft 69 will be oscillated, first in the direction of the arrow shown in Fig. 13 and then backward. This rocking of the shaft 69 will carry the arm 200 downwardly, thereby camming the slide 192 further rearward by the bevel portion 199 of the arm 200 contacting with the roller 198 mounted upon the slide 192.

As previously described, the operation of the key 39 will carry the slide rearwardly, so that the end of the bifurcated portion 195 will contact with the pin 201 on the lever 202. It will be seen from this that the further movement of the slide 192 will be conveyed to the lever 202, which in turn will rock the shaft 205 by means of the arm 204. The shaft 205 extends through to one side of the machine as shown in Figs. 3 and 7, and has fastened to its end a downwardly projecting arm 211, to which is fastened one end of a link 212. The other end of said link is secured to the lower end of an arm 213, by a pin 214, the upper end of which is secured to one of the eccentric bearings 182.

It will be seen from the above description, that when the "total" key 39 is depressed and the handle 131 turned, the shaft 69 will be rocked, which in turn will rock the shaft 205; and the latter by the above described intervening mechanism will rotate the eccentric bearings 181 of the shaft 182 in the direction of the arrow, as shown in Fig. 7, thereby raising the feed roller 180 into contact with the printing cylinder 183 and feed the check paper 179 forward as the rollers are turned. This raising of the roller 180 will also raise the cam disk 184, which in turn will slightly raise the platen slide 188 by means of the lever 187. This raise of the platen slide is such, that when given its two 130

reciprocations by the cam groove 185 the platen 190 will force the inking pad 123 into contact with the total printing wheels 98 and then carry the check paper 179, which 5 has been previously fed forward, against the type wheels to receive an impression, which is similar to the method for printing upon the record strip. The platen slide 188 also carries a knife 216, which in connection 10 with a stationary knife 217 severs the check strip when the platen is raised to take an impression from the type wheels. This check may be then handed to the customer as a receipt for the amount of the purchase. 15 The check is fed from a suitable roll (not shown), which may be located at any convenient place upon the machine, through the chute 179^a pivotally mounted upon a shaft 179^b, between the feed roller and the printing cylinder to the knives 216 and 217. The check chute 179^a also carries a felt roller 179^c for inking the type upon the printing cylinder 183.

All of the printing wheels 87 and 98 are 25 provided with alining disks, which are provided with recesses 219. Pawls 220, mounted upon a shaft 221, are suitably connected so that they move together. One of said pawls has a rearwardly projecting arm 222, 30 which is provided with a roller 223 that plays in a cam groove 224 formed in the gear 147. The shape of the groove is such that after the type wheels have been set, the pawls 220 are rocked into the recesses 35 219 to aline the wheels and remain there until the printing has taken place.

A plurality of department totalizers 225, see Figs. 10 and 11, are mounted upon a reel 226 which is rotatably mounted in a vertically movable frame 227. This frame is raised and lowered by a disk 228 secured to the left hand end of the shaft 104, and which is provided with a cam groove 229. The frame 227 is provided with a roller 230 which plays in the groove 229. A series of nested sleeves 18, to the inner ends of which are secured the intermediate gears 4, are provided at their outer ends with segments 230^a which actuate the pinions 231 attached to 45 the wheels of the counters 225 when the reel 26 is raised by the cam disk 228, as fully described in the aforementioned patent. To the inner side of the reel 226 is secured a pinion 232, which meshes with a segment 50 233 mounted upon a shaft 234. Attached to the side of the segment 233 is a smaller segment 235 which meshes with a segmental rack 236 formed upon the lower end of a setting lever 237. This lever is loosely 55 mounted upon the rock shaft 69 and has pivoted at its upper end a pinch lever 238, which has a foot 239 that depresses an arm 240 whenever the pinch lever 238 is operated. The arm 240 is pivoted to the lever 60 237 by links 241 and has secured thereto a

block 242, shown by a dotted line in Figs. 10 and 11, which normally rests in one of a series of recesses 243 cut in a plate 244 secured to the register frame. The arm 240 is normally forced outwardly by suitable 70 spring mechanism not shown and forming no part of this invention. A suitable index plate (not shown) bearing inscriptions relating to the different counters, is arranged to be mounted upon the front of the register 75 frame adjacent to the path of movement of the setting lever 237. Loosely mounted upon the shaft 69, and fastened to the lever 237, is a segmental rack plate 245, which carries an anti-friction roller 246 that plays 80 in a cam slot 247, formed in an arm 248 secured to a transverse shaft 249, which supports the nested sleeves 83. The other end of the shaft 249, see Figs. 3, 4 and 8, carries a segment 250, similar to the segment 85 84, which meshes with a pinion 251 secured to one end of the outermost one of the nested sleeves 86, to the other end of which is secured the department printing wheel 252.

It will be seen from the foregoing description that should it be desired to register, for instance, cigars 25¢ and drinks \$1.00, the operator would first press the 25¢ key, set the totalizer reel to "Cigars" and then operate the machine. This will result in 25¢ 90 being registered in the "cigars" counter, and the indicators and the two sets of printing wheels being turned forward to bring 25 to printing position. The detail type wheels and the department wheel will be inked, and 95 then the record strip carried against the type upon the further operation of the machine. While the record strip will also be carried against the total printing wheels, no impression will be made upon this portion 100 of the strip because of the fact that the strip at this point is not carried with sufficient firmness against said wheels on account of the total printing platen not being coupled to the detail printing platen. The operation 105 110 is then repeated with the \$1.00 transaction, except that the reel is first set to "Liquors" or "Wines." Previous to the last operation of the machine, however, the "total" key is pressed, which so couples the devices that 115 when the crank handle is turned, the indicators of the accumulator or totalizer will be disclosed and show the total amount, that is, \$1.25. This amount, in connection with the \$1.00 transaction, will also be printed on 120 the detail strip, and a check will be issued showing the total amount. From this it will be seen that any desired number of details or items may be registered up to the capacity of the machine, which in the present instance 125 is nine totalizers, and the total of these details finally indicated to the customer; the details and the total being printed on the detail strip, while only the total is printed on the check. At the end of the day's busi- 130

ness the proprietor can ascertain at once the total amount of business he has done in each department, and also the total of the day's business from the grand totalizer.

5 The expression "digit carriers" is used in the claims in a broad sense to designate either the "indicators" or the "type wheels" geared thereto.

10 By the terms "accumulator" and "totalizer" used throughout the specification and claims is meant any device which accumulates the total of a plurality of items and from which the total may be obtained by reading it from the elements of the accumulator or totalizer, or have said elements record it so that it may be read or in any other suitable manner.

15 While the form of mechanism herein shown and described is admirably adapted to fulfil the objects primarily stated, it is to be understood that it is not intended to confine the invention to the one form of embodiment herein disclosed, for it is susceptible of embodiment in various forms all coming 20 within the scope of the claims which follow.

25 Having thus described my invention, what I claim as new and desire to secure by Letters Patent is:

1. The combination with an operating 30 mechanism, of a series of indicators arranged to show a sum total of different items entered, means for concealing the indicators, means for turning the indicators to zero, and a device for controlling the concealing 35 means and the turn-to-zero means whereby the indicators are turned to zero after being first disclosed.

2. In a machine of the class described, the combination with an operating mechanism, 40 of a series of indicating elements, means for concealing said elements, a special manipulative device, and an element, constantly driven by said operating mechanism, and constructed to be moved under control of 45 said manipulative device into and out of a position for engagement with an element of said concealing means.

3. In a machine of the class described, the combination with an operating mechanism, 50 of a series of digit carriers having printing type connected thereto, a platen for taking impressions from said type, devices for operating said platen, continuously connected to said operating mechanism but normally 55 disconnected from said platen, a special manipulative device, and devices controlled thereby for connecting said platen to its operating mechanism.

4. In a machine of the class described, the 60 combination with an operating mechanism, of a series of indicating elements, designed to exhibit a total of items entered, means for concealing said indicating elements, a cam for withdrawing said concealing means from 65 concealing position, and constantly driven

by said operating mechanism, a special manipulative device, and connections controlled by said manipulative device constructed to move said cam into and out of a position for engagement with an element of said concealing means. 70

5. The combination with an operating mechanism, of a series of indicators arranged to show a sum total of the different items entered, means for turning the indicators to zero, and means for preparing the turn-to-zero means for operation upon the next succeeding operation of the machine. 75

6. The combination with an operating mechanism, of a series of digit carriers arranged to set up a sum total of the different items entered, means for turning the digit carriers to zero and means for preparing the turn-to-zero means for operation as the last item is entered in the total. 80

7. In a machine of the class described, the combination with a series of indicators for accumulating the sum total of a plurality of items, of means for normally concealing the indicators, and means for disclosing the indicators at will and as an accompaniment to the addition of the last item. 85

8. In an accounting machine, the combination with a series of digit carriers for accumulating the sum total of a plurality of items, of means for turning the digit carriers to zero, and a selecting device for controlling the preparation of the turn-to-zero means for operation as an accompaniment to the addition of the last item. 90

9. In a machine of the class described, the combination with an operating mechanism, of a series of indicating elements, designed to exhibit a total of items entered; means for concealing the indicating elements, means for resetting said elements to normal zero position, and a manipulative device, with an element shifted by said device and constructed to be driven by said operating mechanism and thereby to actuate both said concealing means and said resetting means. 95

10. In a machine of the class described, the combination with an operating mechanism, of a series of indicating elements, means for concealing said elements, a cam constructed to operate both said concealing and said resetting means, and driven by said operating mechanism, a special manipulative device, and connections controlled by said device for shifting said cam into and out of a position for actuating said concealing and said resetting means. 110

11. The combination with an operating mechanism, of a plurality of counters upon 115 which different items may be registered, a series of indicators for accumulating a sum total of different items, a series of type carriers for recording upon a record strip the different items, a second series of type car- 120

- riers for recording upon the strip the totals of different items, and a special type carrier actuated according to the counter operated.
12. The combination with an operating mechanism, of a plurality of counters upon which different items may be registered, a series of indicators for accumulating a sum total of different items, a series of type carriers for recording upon a record strip the different items, a second series of type carriers for recording upon the strip the totals of different items, means for turning the indicators to zero at will and means for preparing the turn-to-zero means for operation upon a succeeding operation of the machine. 15
13. The combination with an operating mechanism, of a plurality of counters upon which different items may be registered, a series of indicators for accumulating a sum total of different items, a series of type carriers for recording upon a record strip the amounts of the different items, and a second series of type carriers for recording upon the strip and also upon a check the totals shown on the accumulating indicators. 20
14. The combination with a series of indicators for accumulating sum totals of different registered items, of a series of type carriers for recording upon a strip the different items, and a second series of type carriers geared to the indicators, for recording upon the strip and also upon a check the total of the different items. 25
15. The combination with a plurality of accumulating elements, each being provided with a heart cam, of differentially movable actuating devices for said elements, driving mechanism for the actuating devices, and means normally disconnected from the driving mechanism but capable of connection therewith for resetting the accumulating elements to zero by engaging the heart cams upon an operation of said driving mechanism. 30
16. The combination with a plurality of accumulating elements, each being provided with a heart cam, of differentially movable actuating devices for said elements, driving mechanism for the actuating devices, pivotal members coöoperating with the heart cams of the accumulating elements, a manipulative device, and means controlled thereby for establishing operative relation between the pivotal members and the driving mechanism so that upon the operation of the latter the pivotal members will reset the accumulating elements to zero. 35
17. The combination with a series of type carriers for recording an itemized statement, of a second series of type carriers for printing the total of said statement, and means for controlling the printing of the total as an accompaniment to the printing of the last item. 40
18. The combination with means for re-
- cording upon a record strip an itemized statement, of means for recording the total of said statement upon the strip, and means operable at will for controlling the recording of the total as an accompaniment to the recording of the last item. 45
19. The combination with means for recording upon a record strip an itemized statement, of means for recording the total of said statement upon the strip, and also upon a check, and means operable at will for controlling the recording of the total as an accompaniment to the recording of the last item. 50
20. The combination with an operating mechanism, of a series of counters upon which different items may be registered; a series of indicators for accumulating sum totals of registered items; a series of type carriers for recording upon a record strip the amounts registered at each operation of the machine; a second series of type carriers connected to the indicators for recording totals upon the strip, and also upon a check; a concealing means for the indicators; means for turning the indicators and the total type carriers to zero; and means for controlling the recording of the total, disclosure of the indicators and the preparation of the turn-to-zero means for operation. 55
21. The combination with a series of indicators for accumulating sum totals of a plurality of items, of manipulative devices for controlling the different items accumulated by the indicators, means for concealing the indicators and means for disclosing the indicators as an accompaniment to the addition of the last item. 60
22. In a machine of the class described, the combination with a plurality of indicators arranged to show the sum total of different items entered by successive operations of the machine, means normally concealing the indicators, means for returning the indicators to zero and a special controlling device operable at will, for disclosing the indicators and thereafter causing their return to zero before another item is entered thereon. 65
23. In a machine of the class described, the combination with accumulating digit carriers, of means for concealing the same, and mechanism whereby the digit carriers after being disclosed, must be turned to zero before another item can be entered thereon. 70
24. In a machine of the class described, the combination with printing devices including type carriers for printing details of transactions, of an operating mechanism having connections for taking an impression from said detail type carriers at each actuation of said operating mechanism, additional type carriers for printing totals, and a total key and connections for causing an impression to be taken from said total type. 75

carriers by said operating mechanism, said total impression being taken beside the last detail item making up such total.

25. The combination with means for recording upon a record strip an itemized statement, of means for automatically recording the total of said statement upon a check and issuing the latter as an accompaniment to the recording of the last item upon the record strip. 70

26. In an accounting machine, the combination with a totalizer, of means for clearing it and adding an item thereto during a single operation of the machine. 75

27. In an accounting machine, the combination with a totalizer, of manipulative devices for determining the amounts to be added thereto, means for clearing the totalizer, and means for adding an amount determined by the manipulative devices to the totalizer during the same operation of the machine in which the totalizer is cleared. 80

28. In a machine of the class described, the combination with manipulative devices, and devices controlled thereby for printing details of each item entered in the machine, of total printing type carriers positioned to print in a different column from the printed details making up a total, and a special manipulative device for determining when a total shall be printed. 85

29. The combination with manipulative devices, of means controlled thereby for recording upon a record strip an itemized statement and the total thereof, the construction being such that the total is recorded in a separate column from the items and as an accompaniment to the recording of the last item, and means for predetermining when the total is to be recorded. 90

30. In a machine of the class described, the combination with a printing totalizer, of means for taking impressions therefrom on a record material, devices for resetting said totalizer to zero reading, an operating mechanism, and connections therefrom for operating said impression means and said zero resetting means in automatic succession. 105

31. In a machine of the class described, the combination with a printing totalizer and means for taking impressions therefrom, of devices for resetting said totalizer to zero reading, a special key, a main operating mechanism, and connections controlled by said special key whereby actuation of said operating mechanism operates said impression means and said zero resetting means in automatic succession. 110

32. In a machine of the class described, the combination with a printing totalizer and means for taking impressions therefrom, of devices for resetting said totalizer to zero reading, a special key, a main operating mechanism, devices controlled by said special key for causing operation of said 115

impression means, and a shiftable element moved by said main operating mechanism to engage and operate said zero resetting means, with connections controlled by said special key for shifting said element. 120

33. In a machine of the class described, the combination with a printing totalizer, and means for taking impressions therefrom on a record material, of devices for resetting said totalizer to zero reading, a special key, 75 a main operating mechanism, connections from said main operating mechanism and made effective by said special key for operating said zero resetting means, and connections from said operating mechanism for operating said impression means before the totalizer is reset. 80

34. In a machine of the class described, the combination with a printing totalizer, and means for taking impressions therefrom on a record material, of devices for resetting said totalizer to zero reading, including an actuating arm, a special key, a main operating mechanism and a cam driven thereby, connections controlled by said special key for engaging said cam and said actuating arm thereby automatically to reset said totalizer, and connections from said operating mechanism and also controlled by said special key for operating said impression means. 95

35. In a machine of the class described, the combination with an accumulating indicator and a device for concealing it, of means for resetting said indicator to zero 100 reading, a special key, a main operating mechanism, and an element driven by said main operating mechanism and movable under control of said key to a position wherein it may withdraw said concealing device and then operate said resetting means. 105

36. In a machine of the class described, the combination with an accumulating indicator, and a device for concealing it, of means for resetting said indicator to zero 110 reading, a special key, a main operating mechanism, and a normally ineffective cam driven thereby, and connections controlled by said special key for moving said cam into a position effective to withdraw said concealing device and to operate said resetting means. 115

37. In a machine of the class described, the combination with an accumulating indicator and a device for concealing it, of a special key, a main operating mechanism, connections from said main operating mechanism and controlled by said special key for withdrawing said concealing device when said key is operated, and means for resetting said indicator, said last means being positioned to be operated by said special key controlled connections. 120

38. In a machine of the class described, the combination with an accumulating indi- 130

cator, and a device for concealing it, of means for resetting said indicator to zero reading, a special key, a main operating mechanism and an actuating cam driven thereby, and devices controlled by said special key for shifting said actuating cam to a position wherein it may first withdraw said concealing device and may thereafter actuate said zero resetting means, on actuation of said main operating mechanism.

39. In an accounting machine, the combination with an operating mechanism therefore, of means for recording upon a record strip an itemized statement and the total thereof, and means controlling the recording of the last item and the total during a single operation of the operating mechanism.

40. In an accounting machine, the combination with an operating mechanism therefore, of means for recording upon a record strip an itemized statement and the total thereof, the total being recorded in a manner to distinguish it from the items, and means controlling the recording of the last item and the total during a single operation of the operating mechanism.

41. In an accounting machine, the combination with means for listing a series of items upon a plurality of operations of said machine, of means normally inoperative for listing the total of said items, and means for rendering the total listing means operative upon one of a plurality of operations of the machine, which operations do not exceed the number of items comprising the total.

42. In an accounting machine, the combination with a plurality of totalizers on which amounts may be separately added, of a plurality of accumulators, means for accumulating on said accumulators amounts added on all said totalizers, means for printing the accumulations on said accumulators at will, and a grand totalizer actuated with said accumulators and thereby serving to retain a grand total of all totals separately printed from said accumulators.

43. In a machine of the class described, the combination with accounting devices, of a printing couple brought together each time an item is entered in the accounting devices, a second printing couple arranged to be brought together by the first printing couple when the last item of a series is entered in the accounting devices.

44. In a machine of the class described, the combination with accounting devices in which a series of items may be entered according to a predetermined classification, a printing couple arranged to print each item entered in the accounting devices a second printing couple arranged to print the total of items printed by the first mentioned couple, and manipulatively controlled means for causing the first mentioned couple to op-

erate the second couple as an accompaniment to printing the last item of the series.

45. In a machine of the class described, the combination with an operating mechanism, of a platen operated on every operation of the operating mechanism, a normally inoperative platen, manipulative devices, and means controlled by said manipulative devices for coupling the normally inoperative platen to the invariably operated platen.

46. In a machine of the class described, the combination with an operating mechanism, of a series of item printing type carriers and a series of total printing type carriers, a platen operated to take an impression from the item printing type carriers on every operation of the operating mechanism, a normally inoperative platen for the total printing type carriers, and manipulatively controlled means for connecting the total printing platen to the item printing platen on total printing operations.

47. In a machine of the class described, the combination with an operating mechanism, of an impression taking means operated on every operation of said operating mechanism, a normally inoperative impression taking means, manipulative devices, and means controlled by said manipulative devices for coupling said normally inoperative means to the invariably operated means.

48. In a machine of the class described, the combination with an operating mechanism, of an impression taking means operated on every operation of the operating mechanism, a normally inoperative impression taking means, a slide movable to connect said normally inoperative means to the invariably moved means, and manipulative means controlling the movement of the slide to establish said connection.

49. In a machine of the class described, the combination with an operating mechanism, of a series of total printing type carriers, means operated to take an impression from the item printing type carriers on every operation of the operating mechanism, a normally inoperative means for taking an impression from the total printing type carriers, and means for causing the item printing impression taking means to operate the total impression taking means on total printing operations.

50. In a machine of the class described, the combination with an operating mechanism, of a series of item printing type carriers, a series of total printing type carriers, means operated to take an impression from the item printing type carriers on every operation of the operating mechanism, a normally inoperative means for taking an impression from the total printing type carriers, and manipulatively controlled means for causing the item impression taking

means to operate the total impression taking means on total printing operations.

51. In a machine of the class described, the combination with an operating mechanism, of a series of item printing type carriers, a platen operated to take an impression from the item type carriers on every operation of the operating mechanism, a series of type carriers arranged to accumulate the total of items printed by the item type carriers, and manipulatively controlled means for connecting the total printing platen to the item printing platen, thereby printing the total as an accompaniment to the printing of the last item included in the total.

52. In a machine of the class described, the combination with an operating mechanism, of a series of item printing type carriers, means operated to take an impression from the item type carriers on every operation of the operating mechanism, a series of type carriers arranged to accumulate the total of items printed by the item type carriers, manipulatively controlled means for causing the total printing impression taking means to operate the item printing impression taking means, thereby printing the total at the same time that the last item included in the total is printed.

53. In a machine of the class described, the combination with an operating mechanism, of a series of item printing type carriers, means operated to take an impression from the item type carriers on every operation of the operating mechanism, a series of type carriers arranged to accumulate the total of items printed by the item type carriers, manipulatively controlled means for

causing the total printing impression taking means to operate the item printing impression taking means, thereby printing the total at the same time that the last item included in the total is printed, and means effective on the total printing operations for automatically restoring the total printing type carriers to zero.

54. In a machine of the class described, the combination with an item printing mechanism, of a mechanism arranged to accumulate and print the total of items printed by the first mentioned mechanism, and means for actuating the latter mechanism as an accompaniment to the operation of the item printing mechanism, and means effective on total printing operations only for automatically restoring the total printing mechanism to zero.

55. An accounting machine having means for listing items and the total thereof by a number of operations of the machine not exceeding the number of items comprising the total, and means for automatically clearing the total listing means as an incident to the total printing operation.

56. An accounting machine having means for listing items and the total thereof, and restoring the total listing mechanism to zero by a number of operations of the machine not exceeding the number of items comprising the total.

In testimony whereof I affix my signature in the presence of two witnesses.

WILLIAM H. MUZZY.
